UNITED STATES PATENT OFFICE.

WILLIAM A. SHELY, OF CHICAGO, ILLINOIS.

MACHINE FOR BREAKING, SCUTCHING, AND CLEANING HEMP OR OTHER FIBROUS MATERIAL.

Application filed June 3, 1920, Serial No. 386,328. Renewed September 24, 1923.

To all whom it may concern:

Be it known that I, WILLIAM A. SHELY, a citizen of the United States, residing in Chicago, in the county of Cook and State 5 of Illinois, have invented certain new and useful Improvements in Machines for Breaking, Scutching, and Cleaning Hemp or Other Fibrous Material, of which the following is a specification.

- 10 This invention relates to that class of machines for breaking and scutching and cleaning hemp or other fibrous material, having means for breaking or loosening the hurds or shives from the fibrous material 15 of stalks of hemp or other fibrous material, such as flax, jute, malva, ramie, parini, or similar material, and for removing or separating the hurds or shives from the fibrous material.
- 20 It also relates to improvements in machines for breaking and scutching or treating and cleaning hemp or other fibrous material, having one or more beater bars each mounted on a rotative support and adapted 25 to engage fibrous material to be fed into position to be operated upon thereby, and means for supporting fibrous material in position to be fed to and operated upon by the beater-bar mechanism; and also to 30 improvements in means for separating the hurds or shives from the fibrous material as the stalks of fibrous material are passing from the beater mechanism of the above mentioned form or other form of beater 35 mechanism, and to the means for supporting and operating the beater mechanism.

The principal object of the invention is to provide a simple, economical and efficient machine for breaking and scutching 40 or treating and cleaning hemp, flax, jute, malva, ramie, parini, or other fibrous material; and to means for separating and removing the hurds or shives from the outer or fibrous portions of stalks of fibrous material.

45 Other and further objects of the invention will appear from the following description and claims, and from the accompanying drawings which are made a part of this specification.

The invention consists in the features, combinations, details of construction, and arrangement of parts herein described and claimed.

In the accompanying drawings—

55 Figure 1 is a view in longitudinal central vertical section of a machine constructed in accordance with my invention.

Fig. 2, is a plan view of the machine 60 shown in Fig. 1, with the central portion of the machine and some of the parts broken away, for the purpose of clearly illustrating the mechanism, and the construction and arrangement and mode of operation 65 of the parts:

Fig. 3, is a view in central vertical section of another or modified form of the forward breaking and scutching, or fiber-supporting and beating, cleaning and feeding mechanism; and

70 Fig. 4, is a view in transverse elevation of the mechanism shown in Fig. 3, partly in section—the portion of said Figure 4 on the right hand side of the figure from its center, being taken on approximately 75 section line 4—4 of Fig. 3, looking forward, as indicated by the arrows, with the central part of the mechanism and certain other parts of the machine broken away or shown in elevation for the purpose of clearness 80 of illustration; while the part of the Figure 4 on the left hand side of the center of the figure, shows the machine as it would appear in approximately vertical section on irregular line 5—5 of Fig. 5, looking forward 85 as indicated by the arrows, the bearings shown being on said section line, and the gears there shown being in elevation, with other parts broken away or omitted, for the sake of clearness and in order to 90 avoid unnecessarily illustrating duplicate parts.

Fig. 5 is a view in side elevation of the mechanism shown in Fig. 3, and 4;

95 Fig. 6 is a view in side elevation of a modification of the driving mechanism and beater-bar guiding mechanism; and Fig. 7, a plan view of the driving and bar-guiding mechanism shown in Fig. 6.

100 In constructing an improved machine for breaking and scutching and cleaning or treating hemp, flax, jute, malva, ramie, parini, or other fibrous material, in accordance with my invention, I provide a main frame which, when constructed as shown in Figs. 1 and 2 of the drawings, comprises outer parallel main side frames or frame members 1, 1, a front transverse

frame member 2, a transverse back frame member 3, a transverse intermediate main or bottom frame member 4, which may be secured at its opposite ends to the outer side frame members 1, 1, and may also be secured to the intermediate longitudinal parallel bottom frame members 11, shown in Fig. 1; and bottom transverse frame members or bars 5 and 6, which may be connected with the main outer bottom side frame members 1, 1, by means of brackets 7, and 8, and are adapted to serve, if desired, as axles. It is obvious that any suitable means may be employed for securing the bars or axles 5 and 6 in position.

Front wheels 9, and rear supporting wheels 10, or any desirable suitable form of running gear or supporting means, may be provided.

20 Inner intermediate longitudinal bottom main frame members 11, 11—shown in Fig. 1—are arranged in parallel relation to the outer frame member 1, 1, and secured at their opposite ends to the transverse end frame members 2 and 3.

25 Upright outer side frame members 12, 12, are rigidly secured to and extend upwardly from the opposite outer bottom side frame members 1, 1, and may be secured to the latter by means of bolts 13, or other suitable securing means.

30 Inner upright frame members 14, 14, are fixed at their bottom ends to frame members 11, 11, between the side frame members 12, in position to support the stationary break-bars or fiber-supporting means, and feeding mechanism hereinafter described.

35 An upper front transverse frame member or bar 15, is secured at its opposite extremities to the upright frame members 14; and a similar upper transverse frame member 16 is rigidly secured at its opposite ends, to the tops of the upright frame members 40 12, 12.

45 A suitable cover 17 may be secured in position by means of hinges 18, or other suitable securing means; and a casing 19 of sheet metal may inclose all or any desired part of the machine.

50 Mounted upon the inner upright frame members or standards 14, 14, is a pair of break bars—which are by preference stationary—consisting of an upper break-bar 55 23 and a lower break-bar 24 mounted in parallel superposed relation, with their rear fiber-engaging and breaking edges 25 and 26 spaced apart and facing rearward toward the rotary beater-bar mechanism hereinafter described, so as to provide a passage 60 27 between said break-bars, adapted to permit the passage of stalks of hemp or other fibrous material to be operated upon. Each of these stationary break bars is, by preference, provided with angular end portions

28, at its opposite extremities, adjustably mounted but adapted to be rigidly secured in a slotted portion 29 in the corresponding inner upright standard or frame members 14, 14. The angular end portions of the 70 break-bars may be of suitable width up and down, so that they will meet when the fiber-engaging edges are a suitable distance apart, or they may be separated or spaced apart and each mounted separately and independently upon a suitable support, or each in a separate slot 29, as desired.

75 The angular end portions of the break-bars here shown, are adapted to be secured in rigid operative position by any suitable 80 securing means, such, for instance, as screws or bolts 30 anchored in the standards and in securing engagement with the break-bars; and the break-bars, or the angular end portions thereof, may be provided with horizontal apertures adapted to admit axles 31 and 32 of the upper feed roll 33, and the lower feed roll 34, respectively.

85 The axle 32 of the lower feed roll is mounted in suitable journal bearings in the frame of the machine, such—for instance—as frame members 12, or 12 and 14; and the axle 31 of the upper feed roll 33 extends through elongated openings or movable bearings 36—its opposite ends being, by preference, journaled in suitable slidably mounted bearing blocks 37, which may be in the form of any desired ordinary and well known type of spring-pressed bearing block. One or more spur gears 35, fixed to the shaft 31, are in toothed engagement with one or more corresponding spur gear wheels 38, fixed to the shaft 32 of the bottom feed roll 34, said gears being provided with elongated gear teeth, and said feed rolls being operatively connected with a suitable source of power by any desired ordinary and well known means, such—for instance—as sprocket wheel and chain mechanism. A very desirable form of driving mechanism for the feed rolls will be found described and shown in my co-pending allowed application Serial No. 266,570, filed December 13, 1918, (Patent No. 1,342,772, June 8, 1920) for an improvement in machines for breaking and scutching hemp or other fibrous material, to which attention is directed.

90 100 105 110 115 120 125 130 Mounted back of and in parallel relation to the upper break-bar 23 in position to move downward toward and cooperate with the rear fiber-engaging or breaking edge 26 of the lower break-bar 24, is a series of parallel non-invertible revolving beater-bars 44, each of which is pivotally supported at its opposite ends upon a rotative support consisting of or comprising a bar-supporting disk or wheel 45 rotatively mounted at each end of said series of upper beater-bars, each of said wheels being provided with a stub

shaft, axle or supporting journal portions 47 fixed thereto and journaled in suitable bearings 48' in the frame. These axles or end journals 47 constitute enlarged end portions 5 of a central shaft 49', of smaller diameter. Said shaft 49' extends across from one to the other of said wheels 45, and in fixed relation to and at the axial center of said wheels. Connecting rods 48 are fixed 10 to the wheels 45, and rigidly connect the same, thus forming a rotary bar-supporting frame which is journaled at its opposite ends on the outside of the opposite extremities of the pivoted beater-bars, each of which 15 is pivotally mounted or journaled upon such rotative support in journal bearings in the wheels 45.

Each of the beater-bars 44 is provided at its opposite ends with strong, preferably reinforced end portions 49 to each of which is fixed a strong journal portion, crank shaft or axle 50, which serves to support and pivotally connect each beater-bar with its rotative support.

25 To the outer extremity of each crank shaft 50 is fixed a crank arm 51. These crank arms are each located on the outside of the corresponding bar-supporting wheel 45; and a preferably stationary eccentric or 30 bearing 52 having an opening 53 therein through which the corresponding journal or axle 47 extends, is secured to the adjacent frame member in eccentric relation to the axle 47 and on the outside of the adjacent 35 bar-supporting wheel 45, by means of a central pin or boss 54, or other suitable securing means.

Rotatively mounted on each eccentric bearing 52 is an eccentric ring or gear 55—40 eccentric with respect to the wheels 45 and their journals or supporting bearings, but concentric with respect to the bearing 52—which gear 55 is operatively connected with the series of adjacent cranks 51 in such a 45 manner as to guide the cranks and thereby the series of beater-bars, there being a pair of said eccentric gears 55, one at each end of the rotative supporting frame or drum, the opposite ends of which are formed by 50 the gear wheels 45, 45. This is accomplished by preference as follows: Each crank 51 is provided with an elongated slot 56, and the eccentric rings or gears are each provided with a series of guiding studs or 55 pins 57—in this instance 3—spaced apart uniformly and at equal distances from the axial center of the ring or eccentric gear. There is one of said studs or pins 57 for each crank which is to be operatively connected with such eccentric ring or gear. These studs or pins extend into and operatively engage the slotted portions of the corresponding cranks 51 to be guided thereby. It is obvious that anti-friction bearing 60 blocks of any ordinary and well known form

may be interposed between the pins 57 and the slotted cranks 51, but such bearing blocks are familiar and well known and in common use for forming movable journal bearings for axles or wrist pins, as—for instance—in the case of bearing blocks 37 herein.

70 Mounted back of and in parallel relation to the lower stationary break-bar 24, and in parallel relation to and in position to co-operate with the beater-bars 44, and adapted to move upward in successive order toward and to cooperate with the lower rear fiber-engaging or breaking edge 25 of the upper break-bar 23, is a lower series of beater-bars 58. 75 These lower beater-bars 58 and their rotative supporting and operating mechanism, are constructed and adapted to operate in all substantial respects like the upper series of beater-bars and their rotative support and 80 operating mechanism already described, except that the lower beater bars move upward into striking engagement with the fibrous material and cooperate with the top beater-bars and with the upper stationary break-bar, while the upper series of beater-bars move downward into striking engagement with the fibrous material, and toward the top rear fiber-breaking edge of the lower 85 break-bar, and cooperate with the latter and with the lower series of beater-bars in operating upon the fibrous material to be treated.

90 Each of the lower beater-bars 58 is provided with opposite end portions 59 each having a crank shaft, journal or axle 60 projecting outward endwise therefrom, through an opening or bearing in an adjacent rotative bar-supporting wheel 62 corresponding 95 with the bar-supporting wheels 45 already described. To the outer end of each crank-shaft 60 is fixed a crank arm 61 having an elongated slot 62' therein which is adapted to admit and slidably engage a pin 100 or guiding stud 63 on an eccentric ring or gear wheel 64 which is rotatively mounted upon a preferably stationary eccentric bearing 65, which is mounted upon the frame of the machine, and may be secured to the frame by means of a stud or boss 66, or other 105 suitable securing means. Each eccentric 65 has an opening 67 therein through which extends a shaft or axle 68, which is fixed to the axial centers of or in concentric relation 110 to the axial centers of the lower bar-supporting wheels 62. The shaft or axle 68 is journaled at opposite ends of the rotative beater-bar supporting frame, in suitable 115 bearings 69 in the frame.

120 The bar-supporting wheels 62 are further rigidly connected by means of connecting rods 70 so as to permit freedom of movement of the beater-bars. The beater-bars are thus non-invertible, but are permitted to 125 revolve or travel around the axis of the rota-

tive supporting frame comprising the rotative heads or gear wheels 62, connecting rods 70, and axle or shaft 68, or the rotative support upon which the beater-bars are journaled or pivotally supported.

In operation, the path of movement of the fiber-engaging or breaking edges of the beater-bars is elliptical or approximately elliptical, and eccentric with respect to the axial centers of the rotative supports upon which the beater-bars are pivotally supported. The pivoted beater-bars thus move into and out of engagement with the stalks of fibrous material in successive order in such a manner that the fibrous material will be struck on opposite sides of the layer of said material alternately by the beater-bars of the upper and lower series successively.

The upper and lower series of beater-bars, mounted and adapted to operate as herein described, are operatively connected so as to operate in synchronous relation to each other, by preference, as follows: The upper bar-supporting wheels 45 are each provided with gear teeth 71 which are in toothed engagement with similar gear-teeth 72 on the peripheral rim of the corresponding bar-supporting wheel 62. The rotative eccentric rings or gears 55 are each provided with gear teeth 74 which are in toothed engagement with similar gear teeth 75 on the rotative eccentric wheel 64 at the corresponding end of the series of beater-bars, already described. The eccentrics and the bar-supporting wheels 45 and 62 are thus all so operatively connected that they all have the same number of revolutions per minute, and all rotate and cause the beater-bars to be operated in synchronous relation, all of said 40 rotative toothed gear members being so constructed and arranged and operatively connected that they all have the same number of revolutions per minute.

A main drive shaft 76 is rotatively mounted in suitable journal bearings 77 in the main frame; and a pair of spur gear wheels 78 are each fixed to said shaft, and each in toothed engagement with an adjacent spur gear wheel 79 of a pair of gear wheels each of which spur gears 79 is fixed to the shaft 68 on which the lower pair of bar-supporting wheels 62 are mounted, so that the gears 79 and 62 are in fixed relation, and are operatively connected with and operated by the main drive shaft 76 and the spur gears 78 on said shaft, said gears 79 and eccentric gears 64 being of the same pitch diameter and so operatively connected that they will have the same speed of rotation or number 60 of rotations per minute.

It will be readily seen that in operation the upper and lower series of beater-bars will be caused to revolve in opposite directions, and that each beater-bar will be non-invertible. And the path of movement of

each upper beater-bar will be downward toward and closely adjacent to the upper rear fiber-breaking edge of the lower break-bar and into contact with and in transvers relation to the longitudinal centers of the 70 stalks of fibrous material passing between the break-bars, and then backwards lengthwise of the stalks, and will follow an elliptical path, or approximately an elliptical path—that is to say, the fiber-engaging or breaking edges of the beater bars will move in an approximately elliptical path which is eccentric with respect to the axis of the main rotative beater-bar supporting frame or wheels. And the direction of movement of the fiber-engaging edges of the lower beater-bars into and out of engagement with the opposite side of the layer of stalks or fibrous material will be upward and toward the lower fiber-breaking edge of the upper 85 break-bar, transversely to the length of the stalks, and rearward and downward in an approximately elliptical or curved path which is eccentric with respect to the axis of the lower rotative beater-bar supporting 90 frame and its main end gear wheels 62.

It will be readily apparent to those skilled in the art to which this invention relates that the varying conditions and character of the fibrous material to be treated, or broken, scutched and cleaned, renders it desirable and necessary to the accomplishment of the best results that some stalks or fibrous material should receive more beating, or harder strokes than others, and some should receive more scutching or scraping than others, according to the condition, character and kind or species of fiber or stalks to be treated, stalks that are under-retted or only partially cured requiring more or harder beating and scutching than would be required or good for a batch of over-retted stalks, etc.

The extent and degree of severity of the beating may be regulated by adjusting the beater-bars toward or from the path of movement of the rotary beater-bars, and also by regulating the speed of movement of the beater-bars. And the striking or beating edges of the beater-bars may be made more or less sharp, as required by the condition or kind of stalks of fibrous material. The scraping edges 80 of the beater-bars 45 and 58 may be sharpened and may project beyond the main body of the bar to any desired extent, and may be sharpened by providing a recess 81 above and parallel with the scraping edge or fiber-engaging edge which faces in the direction of movement of the beater-bars, respectively, while in scraping engagement with the stalks or fibrous material.

Suitable scutching and shaker mechanism is provided, which is located back of the beater-bar mechanism, or main breaking 130

and scutching mechanism above described, and is constructed and adapted to operate as follows:

A supporting frame is provided, which 5 may be of any desired suitable form, and which, in this instance, is in the form of a removable or supplementary frame adapted to be mounted upon and secured in any desired position with respect to the main 10 frame, and comprises longitudinal bottom side frame members or sills 82, located on opposite sides of the main frame of the machine, and removably supported by the latter, top side frame members 83, upright 15 side frame members 84 and 85, transverse frame members 86, 87, 88, and 89, each secured at its opposite ends to the upright forward side frame members 84, on opposite sides of the machine, and upper transverse 20 frame member 90 secured to the uprights 85 on opposite sides of the machine frame, a bottom transverse frame member 91, secured to the opposite bottom side frame members 82, and inclined side frame members 25 92, located on opposite sides of the frame and secured to the bottom side frame members 82, and to the upper forward corners of the frame at or near the upper ends of the upright side frame members 84, all 30 of which may be of angle iron construction, or of any desired suitable material for forming such a frame.

A pair of oscillating or vibrating shaker jaws, frames or plates of simple construction 35 and adapted to operate in an economical and efficient manner, is mounted directly back of the upper and lower rotary beater-bar mechanism. These shaker jaws, frames, plates or main upper and lower oscillating 40 shaker members are constructed and arranged as follows:

The upper shaker jaw or frame comprises in its construction a series of ribs or bars 93 45 which are pivotally supported at the forward extremity of the jaw nearest the beater-bars by means of a transverse horizontal pivot rod or shaft 94 which, by preference, extends through the perforated forward ends of all of said ribs 93, said rod being 50 supported in horizontal position by means of hinge members 94' through the lower perforated ends of which said rod extends. The hinge members 94' are secured to the transverse frame member 87 by means of bolts 96 55 or similar securing means. A plate 97, which may be made of sheet metal extends beneath the series of ribs 93 and is folded over the shaft 94, and pivotally supported by the same, and secured to the ribs by means 60 of a rod 98 which is secured to the rear swinging portions of the ribs and extends along the under side of the rear marginal portion of the plate which is bent upward and over said rod, so as to be held in place 65 and securely connected with the ribs and

rod, to form a strong, well braced, and comparatively light structure or upper shaker jaw. A similar lower shaker jaw is mounted beneath and in approximately parallel relation to the upper jaw, and spaced apart from the latter so as to provide a passage between the upper and lower oscillating or vibratory pivoted jaws adapted to permit hemp or other fibrous material to pass rearward between the jaws from between the beater-bars, while the shaker jaws are rapidly shaking or oscillating so as to shake the layer of hemp or other fibrous material passing between the jaws, and loosen and separate the hurds or shives from the fibrous material and permit the cleaned fibrous material to be removed or pass rearward from between the rear rapidly swinging extremities of the jaws. This lower jaw comprises in its construction a series of ribs 99 which are, by preference, pivotally mounted upon a pivot rod 100 located beneath and spaced apart and in parallel relation to the rod 94, and supported by means of hinge members 101 which are secured to the transverse frame member 88 already described. A plate 102 extends over and across the series of ribs 99, and is folded back over and pivotally supported by the rod 100, the rear extremity of said plate 102 being secured to the ribs 99 by means of a rod 103 which extends through and is supported by the rear extremities of all of said ribs, and extends over said rear margin of the plate, so as to rigidly secure and hold the plate in place upon and in engagement with said ribs, thus forming a lower jaw which is of substantially identical construction with the upper jaw, but in inverted relation to the latter. The ribs of the upper and lower jaws are spaced apart, and may extend rearward beyond the free or swinging edge of the plates, so as to permit hurds and shives and waste material to escape from between the ribs as they become loosened and separated from the fibrous material.

A crank shaft 105 is journaled in suitable bearings in the frame, and provided with any desired number of crank arms and wrist pins; and any desired number of pitman rods 106 are mounted upon the wrist pins of the crank shaft, and each connected with the oscillating jaw mechanism above described.

The pitman rods may be connected with the upper jaw in a simple and efficient manner by means of a rod 107 which extends through suitable apertures in all or any desired number of the ribs 93, or any suitable portion of the upper jaw, and through the openings in the corresponding ends of the pitman rods, so that the latter are pivotally connected with the oscillating jaw mechanism and with the crank shaft. The upper and lower jaws are, by preference, connected

at their opposite ends or transverse extremities by means of links 108, one end of each of said links being connected with the rod 107, and the other with a rod 109 which is 5 anchored in or mounted upon the ribs of the lower jaw. Means for enabling the upper and lower jaws to be adjustably secured in such relation to each other as to provide the desired space between the jaws is provided, 10 and may consist of holes 110, 110, in the ribs of the upper and lower jaws, or either of them, adapted to receive the rods 107 and 109 respectively. The length of movement of the jaws upward and downward may be 15 increased and decreased, as desired, by shifting the rod 107 to the holes 110, or from the latter to the holes in which the rod is shown in the drawings, the holes mentioned being located at different distances from the pivot 20 rod or axis of the jaw mechanism.

Suitable feeding means is provided, for feeding the fibrous material into position to pass between the oscillating jaws from the beater-bar mechanism, and may consist of 25 an upper feed roll 111 having its opposite end journals 112 journaled in spring-pressed sliding blocks 113, at opposite sides of the machine frame, and a lower feed roll 114 having its opposite end journals 115 journaled in bearings 116, said rolls being in parallel relation back of and closely adjacent to the path of movement of the upper and lower series of beater bars, and adapted to cause fibrous material passing rearward 30 between the beater-bars, to be fed between the oscillating shaker jaws. A shield 117, suitably weighted or counter-balanced by means of a weight 118 so as to be yieldingly held in contact with and swing upward and 35 downward with the roll 112, is pivotally mounted in position to engage the upwardly moving or rearwardly moving side of said roll, and extend from the roll rearward toward the jaws, so as to guide material from 40 the roll into position to pass between the jaws, and prevent wrapping of fibrous material around the roll; and a similar shield 45 119 is mounted in position to engage the rear upper side of the lower feed roll and extend therefrom rearward toward the pivoted portion 50 of the lower jaw.

A stationary, preferably adjustable, scutching bar 120 is mounted in position to extend transversely across the machine 55 back of and adjacent to the rear swinging margins of the oscillating jaws above described. This bar may be adjustably secured in position by means of headed bolts 121 extending through elongated slots 122 in the angular end portions of the bar, and anchored in the upright side frame members 85.

An upper paddle wheel 123 and a lower paddle wheel 124' are mounted rearward with respect to and in parallel relation to

the bar 120 and the rear swinging margins of the shaker jaws, and are spaced apart so as to permit and cause the passage of fibrous material rearward between the paddle wheels as the fibrous material is discharged from 70 between the shaker jaws.

These paddle wheels may be of identical construction, each consisting of a pair of heads having radial arms 124 extending outward radially from hubs 125 at opposite ends of the paddle wheels, and having paddles 126 mounted upon the radial arms and uniformly spaced apart, each of the paddle wheels having a shaft (127—127'), the opposite ends of which are journaled in 80 suitable bearings in the machine frame, so as to rotatively support the paddle wheels in parallel relation, and in such position that the paddles of each wheel will cross the path of movement of the paddles of the 85 other wheel, and cause fibrous material to be fed rearward between the paddle wheels, with the paddles of the lower paddle wheel in engagement with the under side of the 90 layer of fibrous material, and those of the upper wheel in engagement with the upper side of the layer of material; and so that the rear margin of the upper shaker jaw will move downward closely adjacent to the upwardly moving paddles of the lower paddle wheel, and the rear margin of the lower shaker jaw will move upward toward the lower forward edge of the scatcher bar 120. And the paddles of the upper paddle wheel will move downward past the rear margin 95 or edge of the bar 120, which, rear edge is, by preference located upward and rearward from the front edge of said bar, so as to permit fibrous material to be thrown upward against said bar by the shaker jaws, and 100 shaken and flexed rapidly as the fibrous material passes rearward between the jaws, and between the paddle wheels located back of the shaker jaws, thereby scutching and loosening the hurds from the fibers, and delivering 105 the cleaned fibrous material at the rear of the machine.

An endless apron 128 is mounted at the rear end of the machine on rolls 129, and 110 130, each having its axle journaled at its opposite ends in suitable bearings in the machine frame; and a roll 131 having its axle 132 journaled at its opposite ends in suitable bearings in the frame, extends 115 across the endless apron in parallel relation to the roll 129, and in contact with the front portion of the upper rearwardly moving lap of the endless apron, so as to feed fibrous material rearward from between the shaker jaws and paddle wheels.

A lower endless apron 133, which is for carrying off the hurds, shives or inner woody substances separated from the outer fibrous portions of the stalks is mounted at its forward extremity on a roll 134 having an axle 120 125

135, the opposite ends of which are journaled in suitable bearings in the frame; the rear extremity of said endless apron being mounted on a rear roll 136 having a shaft or axle 137 the opposite ends of which are journaled in bearings on opposite sides of the frame.

The roll 129 has an axle 138; and the roll 130 has an axle 139.

10 All of the moving parts of the machine are of course operatively connected directly or indirectly with the main drive shaft, or with a suitable source of power.

The crank shaft 105, which operates the shaker mechanism or oscillating jaws, is operatively connected with the main drive shaft 76 by means of a sprocket wheel 140 fixed to the shaft 105, a sprocket wheel 141 fixed to the main drive shaft, and a sprocket 20 chain 142 mounted on said sprocket wheels.

The feed rolls 111 and 114 are operatively connected by means of a spur gear wheel 143 on the shaft 112 of the upper feed roll, and a spur gear wheel 144 fixed to the shaft 25 115 of the lower feed roll 114, and in toothed engagement with the gear 143. The shaft 115 of the roll 114, and the shaft 135 of the roll 134 which supports the forward extremity of the endless apron 133, are operatively connected with each other and with the main drive shaft by means of a sprocket wheel 145 fixed to the shaft 115, a sprocket wheel 146 fixed to the shaft 135, a sprocket chain 147 mounted on said sprockets; a

25 sprocket wheel 148 fixed to the shaft 127, a sprocket wheel 149 fixed to the shaft 105 which is connected with the main drive shaft, and a sprocket chain 150 mounted on said sprockets 148 and 149.

40 The lower paddle wheel 124' having a shaft 127 is operatively connected with the upper paddle wheel 123, by means of a spur gear 150' fixed to the shaft 127' of the upper paddle wheel, and a spur gear 151' fixed to the shaft 127 of the lower paddle wheel and in toothed engagement with the gear 150'.

The lower paddle wheel 124' with its shaft 127 is operatively connected with the shaft 115 of the lower feed roll 114 by means of a 50 sprocket 152 fixed to the shaft 127, a sprocket 153 fixed to the shaft 115, and a sprocket chain 154 mounted on said pair of sprockets.

The rear roll 130 which supports the rear 55 portion of the endless apron 128 is operatively connected with the shaft 127 of the lower paddle wheel 124' by means of a sprocket 155 fixed to the axle 139 of said roll 130, a sprocket 156 fixed to the axle 127, 60 and a sprocket chain 157 mounted on said pair of sprockets.

The lower main feed roll 34 on the axle 32 is operatively connected with a source of power by means of a sprocket 158 fixed to 65 the shaft 32, a sprocket wheel 159 fixed to

the shaft or axle 115 of the lower intermediate feed roll 114, and a sprocket chain 160 mounted on said pair of sprockets. And said upper and lower front feed rolls 33 and 34 are operatively connected with each other 70 by means of spur gears on their respective shafts and in toothed engagement with each other, as already described, or by any desired ordinary and well known form of connecting gear mechanism.

A modified form of breaking and scutching machine, shown in Figs. 3, 4, and 5, of the drawings, and embodying my invention, is constructed as follows:

A main frame is provided which may be 80 of any desired ordinary and well known or suitable form, and which, when constructed as shown in said Figures 3, 4, and 5, consists of or comprises a pair of side frames or casings 201, 201, each formed of a front frame member 202, and a rear frame member 203 which are hollowed out and provided with suitable strengthening and connecting flanges, and suitable bearings for supporting the movable parts of the machine 85 to be mounted in and supported by said main frame or side frame members. The frame members 202 and 203, are rigidly connected by means of bolts 204, which extend through suitably perforated portions of flanges 205 of the front side frame members 202, and flanges 206 of the rear main side frame members 203, or by other similar or suitable securing means.

Each of the main side frames is bored out 100 at 207, and provided with suitable bushings or bearings 208 mounted in and forming linings for the bores thus formed in the upper portions of the casing or main side frame members. And similar bores 209 are made in each of the side frames 201, in parallel

relation to the bores 207, and bushings or bearings 208, and provided with linings, bushings or bearings 210. The bearings 208 thus formed on opposite sides of the frame 105 of the machine, are in alignment, and are adapted to form journal bearings or supports for an upper series of beater-bars, and their rotative supports, or supporting wheels or drums, hereinafter more particularly described; and the bearings 210, which are likewise located on opposite sides of the machine and in alignment with each other,

110 serve to form journal bearings or supports for a lower series of beater-bars, and their supporting wheels or drums shown in Figs. 3 and 4.

The main side frames or casings 201, 201 are mounted in parallel relation to each other in position to form opposite side frames of the machine, and are rigidly connected by suitable transverse frame members 125 which may consist of or comprise an upper rear transverse frame member or beam 211, and a lower rear transverse frame member

or beam 212, each of which extends across the machine from one side to the other thereof and is secured at each end to the rear main side frame members 203, 203, located on opposite sides of the machine. These transverse frame members or beams have suitable side flanges at the opposite longitudinal margins of their, preferably slightly curved bodies, adapted to afford the desired strength; and are provided with end flanges 213 at each end of each of the transverse beams, having perforations through which extend securing bolts 214, each of which is anchored in an adjacent marginal flange portion of the corresponding rear main side frame member 203, so as to firmly secure the transverse beams and main side frames in rigid relation to each other, and form a strong and rigid main frame, having open front and rear sides, but with closed gear boxes or casings on opposite sides of the main frame thus formed. The front part of the frame members 202, 202, are rigidly connected by means of transverse connecting frame members which may consist of a connecting rod 215, the opposite extremities of which are connected with said frame members 202, 202, respectively, said rod being encircled by means of a hollow shaft or pipe 216, the ends of which abut against the inner faces of said frame members 202, 202, so that by tightening the securing nuts 217 on the threaded ends of the rod, the parts will be tightly drawn and secured in rigid engagement, with the main side frame members properly spaced apart, and held in place by the transverse members 215, 216, and beams 211, 212.

40 Mounted between the side frames 201, 201, and secured to the upper and lower forward portions 219, 220 of the front side-frame members 202, 202, respectively by means of connecting rods 221, 221, is a pair 45 of break-bars—which are by preference stationary—each of which is provided at its opposite ends with perforated projecting angular end portions or securing bosses 28' through which the securing rods or bolts 221 anchored at their opposite ends in the side frame members 202, 202, extend. These break-bars extend transversely across the forward portion of the frame of the machine from side-frame to side-frame, to 50 which their opposite ends are securely attached, and consist of an upper break-bar 23' and a lower break-bar 24' mounted in parallel superposed relation, with their rear fiber-engaging and breaking edges 25' and 55 26' spaced apart and facing rearward toward the rotary beater-bar mechanism hereinafter described, so as to provide a passage 27' between said break-bars, adapted to permit the passage of stalks of hemp or other

fibrous material to be operated upon. Each 60 of these stationary break-bars is, by preference, provided with angular end portions 28' at its opposite extremities adapted to permit the adjustment of the break-bars, but also adapted to be rigidly secured to the 70 side frame members 202, 202, as above indicated. The ends of the break-bars are adapted to be secured in rigid operative position, in any position to which they are adjusted, by any suitable securing means, 75 such, for instance, as screws or bolts 30' anchored in the side frame members at the ends of the break-bars, and in securing engagement—preferably threaded engagement—with the break bars. 80

An upper feed roll 33', having an axle 31'; and a lower feed roll 34' having an axle 32', are mounted in superposed relation in front of the break-bars 23' and 24' and between the side-frames 201, 201, the 85 opposite ends of said axles being journaled in suitable bearings in the machine frame. The axle 31' of the upper feed roll 33' is, by preference, journaled at its opposite ends in suitable upwardly and downwardly movable 90 slidably mounted bearing blocks 37', which may be in the form of any desired ordinary and well known type of spring-pressed bearing blocks, each of which is slidably mounted in a bearing slot 222 in 95 the side frame of the machine and provided with a compressible spring 223 in engagement with each of said bearing blocks and adapted to permit but yieldingly resist the upward movement of the bearing blocks 100 and the upper feed roll 33' supported thereby. One or more spur gears 35' mounted in fixed relation to or operatively connected with the shaft or axle 31' by means of a connecting stub-shaft 224 which 105 is articulately connected with the axle 31' by means of suitable coupling or connecting shaft member 225 having articulate or universal joint connections at its opposite ends, with the angular ends of the stub shaft 224 110 and axle 31', respectively, are operatively connected or in toothed engagement with one or more corresponding spur gear wheels 38' fixed to or operatively connected with the axle 32' of the bottom main feed roll 115 34'. Said gears may be operatively connected by means of a train of gears comprising a spur gear 226 having a hub 227, said gear being loosely mounted on or in rotative relation to the stub shaft 224; a 120 spur gear 228 and spur pinion 229 rigidly connected and both mounted in rotative relation to or loosely upon the axle 32' of the lower feed roll, the pinion 229 being in toothed engagement with the gear 226, and the gear 228 being in toothed engagement with a spur pinion 230 which is fixed to 125 the main drive shaft 76'. The feed rolls

are thus operatively connected with each other and with the main drive shaft, and are adapted to be operated by the latter.

Mounted back of and in parallel relation to the upper break-bar 23' in position to move downward toward and cooperate with the rear fiber-engaging or breaking edge 26' of the lower break-bar 24' is a series of parallel non-invertible revolving beater-bars 44' each of which is pivotally supported at its opposite ends upon a rotative support consisting of or comprising a bar-supporting disk, wheel or drum 45' rotatively mounted at each end of said series of beater-bars, each of said wheels being provided with a hollow drum or short supporting journal or bearing portions or bosses 47' fixed thereto and journaled in suitable bearings 208 in the frame. A central shaft portion or rod 49'', which is by preference triangular in cross-section, and small enough in cross-section to permit the beater-bars 44' to revolve freely without becoming inverted or turning over bodily, extends across from one to the other of said wheels 45', and is fixed at its opposite ends to and at the axial centers of said wheels or drums 45'. Connecting rods 48' are fixed to the wheels 45' and rigidly connect the same, and are arranged at equal distances from each other and at equal distances from the axis of the bar-supporting frame, and at equal distances from the axes of the beater-bars 44', so as not to come in contact with or interfere with the movements of the latter, thus forming a rotary bar-supporting frame which is journaled at its opposite ends on the outside of the opposite extremities of the pivoted beater-bars, each of which is pivotally mounted or journaled upon such rotative support in journal bearings 231 in the beater-bar-supporting wheels 45'.

Each of the beater-bars 44' is provided at its opposite ends with strong, preferably reinforced end portions 49' to each of which is fixed a strong journal portion, crank shaft or axle 50' which serves to support and pivotally connect each beater-bar with its rotative support.

To the outer extremity of each crank shaft 50' is fixed a crank arm 51'. These crank arms are each located on the outside of the corresponding bar-supporting wheel 45'; and a preferably stationary eccentric bearing 52' is mounted upon the adjacent side frame in eccentric relation to the axial centers of the wheels 45' and on the outside of the corresponding adjacent bar-supporting wheels last mentioned.

Rotatively supported upon or by means of each of said eccentric bearings 52' is an eccentric gear 55'—eccentric with respect to the wheels or drums 45' and their journals or supporting bearings, but concentric with respect to the axial center or center of ro-

tation of said gears 55', and the journal-engaging portion of the bearings 52'—which gear 55' is operatively connected with the series of adjacent cranks 51' in such a manner as to guide the cranks and thereby the series of beater-bars, there being a pair of said eccentric gears 55', one at each end of the supporting frame or drum, the opposite ends of which are formed by the gears or drums 45', 45''. This is accomplished by suitable connecting means which may be constructed as follows: Each crank 51' is provided with an elongated slot 56', and the eccentric gears 55' are each provided with a series of studs or pins 57'—in this instance 3—spaced apart uniformly and at equal distances from the axial center of the ring or eccentric gear. There is one of said studs or pins 57' for each crank which is to be operatively connected with such eccentric ring or gear. These studs or pins extend into and operatively engage the slotted portions of the corresponding cranks 51' to be guided thereby. Anti-friction guiding bearing blocks 232—one for each pin 57' are interposed between the crank pins 57' and the slotted cranks 51'. Each of these bearing blocks is slidably mounted in a slot 56' in the corresponding crank arm 51', and has a perforation through the sliding block into or through which the crank pin on which the sliding block is mounted extends. The slots in the crank arms are disposed longitudinally of said crank arms, and may extend throughout the entire length of the latter, so that the slots are open at both ends, and also open in a direction toward the eccentric rotary guiding member or wheel 234 on which the crank pins are mounted, so that the sliding blocks are free to move lengthwise of the slotted cranks in which they are mounted and to extend outward beyond the swinging ends of the cranks when the blocks reach the limit of their path of movement in one direction lengthwise of the cranks, and to project outward beyond the pivoted ends of the cranks when the sliding blocks reach the limit of their path of movement in the opposite direction or toward the pivoted ends of the cranks. I prefer to make the sliding blocks rectangular with flat sides or parallel sides in sliding engagement with corresponding parallel side walls of the slots in which they are mounted, although it is obvious that the shapes of the blocks may be modified or varied, and are not required to be of the identical form shown in the drawings. The rotary eccentric guiding wheel or plate 234 is by preference triangular or three-cornered, and has its periphery hollowed out or concave between the projecting corner portions thereof, so as to permit the adjacent corresponding eccentric guiding member or plate 234' of the adja-

cent rotary eccentric guiding mechanism for the adjacent series of beater bars to rotate in interlapping relation to or as close as practicable to the eccentric member 234.

- 5 Each eccentric guiding wheel or three-cornered angular plate 234 is mounted in fixed relation to a stub shaft 235 which is journaled in a suitable bearing 236 stationary in the corresponding side frame 201, 10 and is provided with a toothed gear wheel 55' rigidly secured in fixed relation to such plate 234 by means of connecting pins or rivets 237, or other suitable securing means adapted to securely hold the plates and their 15 toothed gear wheels and stub shaft in fixed relation to each other, so they all form for all practical purposes, a single rotative guiding member on each side of the machine on the outside of the corresponding toothed 20 beater-bar supporting wheel 45'. Each of the crank arms 51' thus extends between a rotative bar-supporting wheel 45' and a corresponding adjacent eccentric guiding wheel or plate 55'. 25 Mounted back of and in parallel relation to the lower stationary break-bar 24', and in parallel relation to and in position to cooperate with the beater-bars 44', and adapted to move upward in successive order 30 toward and to cooperate with the lower rear fiber-engaging or breaking edge 25' of the upper break-bar 23', is a lower series of beater-bars 58'. These lower beater-bars 35 58', and their rotative supporting and operating and guiding mechanism, are all constructed and adapted to operate in all substantial respects identically like the upper series of beater-bars, and their rotative supports, and eccentric guiding mechanism 40 and operating and connecting mechanism already described, except that the lower beater-bars move upward into striking engagement with the fibrous material, and cooperate with the top beater-bars and with 45 the upper stationary break-bar, while the upper series of beater-bars move downward into striking engagement with the fibrous material, and toward the top rear fiber-breaking edge of the lower break-bar, and 50 cooperate with the latter and with the lower series of beater-bars in operating on the fibrous material to be treated.

Each of the lower beater-bars 58' is provided with opposite end portions 59' each 55 having a crank shaft, journal or axle 60' projecting outward endwise therefrom, through an opening or bearing—like the bearing 231—in an adjacent corresponding 60 rotative bar-supporting wheel 62' corresponding with the bar-supporting wheels 45' already described. To the outer end of each crank shaft 60' of the lower set of beater bars 58' shown in Fig. 3 is fixed a slotted crank arm 61' having an elongated 65 slot 238 therein which corresponds in all

respects with the slots 233 in the crank arms of the upper set of beater bars 51' shown in said Fig. 3, already described, and each slot 238 is adapted to admit a guiding crank pin 63' mounted on an eccentric guiding wheel or three-cornered plate 234' which is of identical construction with the eccentric guiding member 234 already described. There are two eccentric guiding wheels or plates 234', one at each end of the lower 75 series of beater-bars 58'; and each of said eccentric wheels is provided with a toothed gear wheel member 64' which is mounted in fixed relation to the same stub shaft 240 to which such angular eccentric guiding plate 80 or wheel 234' is fixed. On each stub shaft 240—there being one of said shafts on each side of the machine frame, each mounted in suitable eccentric bearings 241, in the main side frames 201—is mounted a toothed spur gear wheel 242, which spur gears are each fixed to the corresponding stub shaft 240 upon which the corresponding eccentric rotative guiding members 234' and 64' are also fixed. These spur gear wheels 242 are both of the same pitch diameter as the toothed beater-bar supporting wheels 62' and 45'. 90

These guiding crank pins 63' each extend into and operatively engage a corresponding slotted portion of a corresponding crank arm 61' which is to be guided thereby. And anti-friction guiding bearing blocks 232—one for each pin 63'—are interposed between the crank pins 63' and the corresponding slotted crank arms 61'. Each of these bearing blocks 232' is slidably mounted in a corresponding slot 238 in the adjacent crank arm 61', and has a perforation through such sliding block into or through which the crank pin on which the sliding block is mounted extends. The slots in the crank arms are disposed longitudinally of said arms, and are, by preference, open at both ends and on the side toward the eccentric guiding member on which the pins are mounted which extend into such blocks. These sliding blocks 232' are constructed identically like and operate in the same manner as sliding blocks 232 already 100 described. 105

The gear-toothed bar-supporting wheels 62' are of identical construction with the wheels 45' already described, and are in tooth-engagement with the latter; and the eccentric toothed gear wheel members 55' and 64' are of identical construction and are each of the same pitch diameter, and in toothed engagement with each other, and all adapted to operate in the same manner. 110

The main drive shaft 76' which extends transversely across the machine from side to side thereof, and is mounted in suitable bearings 244 located on opposite sides of the machine frame, is provided with a pair 115 of spur gears 245 fixed thereto—one for 120

each spur gear 242 on the stub shafts on which the eccentric guiding members 242 and 64' are mounted. Each of these spur gears 245 on the main driving shaft, is in 5 toothed engagement with an adjacent corresponding spur gear wheel 242 on the stub shaft which operates the eccentric guiding wheels 64' and plates 242 already described. It will thus be readily seen that, as the 10 spur gears 242 are of the same pitch diameter as the bar-supporting gear wheels 62', it is only necessary to provide two additional spur gears 246 which are fixed to the main drive shaft 76' in position to each 15 be in toothed engagement with a corresponding adjacent bar-supporting gear wheel 62', to complete the driving mechanism for operating the two series of revolving non-invertible beater-bars, and the 20 rotative supports upon which said beater-bars are pivotally supported, and also the eccentric guiding mechanism by means of which said beater-bars are guided. The beater-bar supporting wheels 62' are further rigidly connected by means of a series 25 of connecting rods 70' in such a manner as to permit freedom of movement of the beater bars on their axle bearings.

The upper toothed gear wheels 45' are in 30 toothed engagement with the corresponding adjacent lower toothed gear wheels 62'; and the gears 55' are in toothed engagement with the corresponding gears 64' at the opposite ends of the upper and lower series of 35 pivoted beater-bars, and on the outside of the gears 45' and 62'. It will thus be seen that, with the driving shaft 76' operatively connected with all of said gears in the manner herein shown and described, all of said 40 gear wheels will be caused to rotate at the same speed of rotation or the same number of revolutions per minute, and the upper series of beater-bars and lower series of beater bars will be caused to strike alternately on opposite sides of a layer of fibrous material to be operated upon thereby, as such layer of fibrous material is caused to pass between such upper and lower series of beater-bars, and between the break 45 bars already described.

In Figs. 6 and 7 is shown another form 50 of breaking and scutching mechanism having beater-bars pivotally mounted on rotative supports, and comprising an upper series and a lower series of beater-bars constructed and adapted to operate in all substantial respects identically as do the beater-bars 44, 58, of Figs. 1 and 2, and beater-bars 44' and 58' of the device shown in 55 Figs. 3, 4, and 5. In said Figs. 6 and 7 is also shown a modified form of guiding mechanism for guiding the beater-bars, and a modified form of driving mechanism for driving the eccentric rotative guiding mechanism, and the rotative supporting wheels

45, 45, and 62, 62, are shown in said Figs. 6 and 7, but with the beater-bars, break bars, shaker mechanism, guiding blocks for engagement with the slotted crank arms of the beater-bars and other parts of the machine 70 omitted or broken away, in order to enable the parts shown in said figures to be clearly illustrated and understood.

In the form of the device shown in said Figs. 6 and 7, the main drive shaft 76 is 75 provided with a pair of spur pinions or gears 300, 300 located at opposite sides of the machine and fixed to said main drive shaft in position to be in toothed engagement with the lower pair of main beater-bar supporting toothed gear wheels 62, 62, which are in turn in toothed engagement with the upper pair of main beater-bar supporting toothed gear wheels 45, 45, which support and operate the upper and lower 80 series of beater-bars in the manner already described, and as illustrated in Figs. 1 and 2.

Fixed to each pinion or spur gear wheel 300, 300, is a pinion or spur gear 301, 301.

And I prefer to connect each pinion 300, 90 with its mate 301 by means of a connecting hub 302. These connected pinions are fixed to the main drive shaft by suitable securing means, and are of the same pitch diameter.

Upper stationary eccentrics or bearing members 52, 52, and lower eccentrics or bearing members 65, 65, are mounted in the side frames of the machine, and constructed and adapted to operate substantially as already described in connection with Figs. 1, 100 and 2 of the drawings, said eccentric being located outside of the 45, 45, and 62, 62, as already described. On each eccentric bearing member 52 is rotatively mounted a spur gear beater-bar-guiding wheel 55, 55, one at 105 each side of the machine; and rotatively mounted on each eccentric 65, shown in said Figs. 6 and 7, is a similar beater-bar-guiding spur gear wheel 64, 64, each of which is in toothed engagement with the corresponding gear 55.

Each of the spur gears 55 has a three-cornered beater-bar guiding plate or wheel 303, 303, fixed thereto, each of said plates having three wrist-pins or crank pins 57, 115 57, 57; and each of the spur gears 64, 64, shown in said Figs. 6, and 7, has a three-cornered plate 304, 304, fixed thereto and adapted to rotate therewith upon the corresponding stationary eccentrics 65, 65. Said plates 303, and 304, are located 120 between the gear wheels to which they are fixed, and the corresponding beater-bar supporting wheels 45, 45, and 62, 62. And the plates or wheels 304 are each provided with a plurality of wrist pins, 63, one for each beater-bar to be guided thereby. The wrist pins 63, 63, 63 are each adapted to extend into and in guiding engagement with corresponding slotted cranks 61, 61, 61; and 130

the pins 57 are adapted to slidably engage and extend into slotted crank arms 51, 51, 51, fixed to opposite ends of the upper series of beater-bars—the crank arms 61 being fixed to opposite ends of the beater-bars forming the lower series of such bars, as already described.

Fixed to and in concentric relation to each of the eccentric spur gear wheels 65, 65, is 10 a spur gear wheel 305, 305, there being one of said spur-gear wheels 305 on each side of the machine. Each of these last mentioned spur gear wheels 305, is in toothed engagement with an adjacent corresponding spur pinion 301, 301, already described.

It will be readily understood by those skilled in the art that with the shafts 47 and 68 each journaled in and extending through a corresponding stationary eccentric 20 52, 65, respectively, the upper and lower rotative supports for the two series of beater-bars, are supported in an efficient manner, and are operatively connected with the main driving shaft, which is also operatively connected with the eccentric guiding mechanism by simple and efficient means, and in such a manner as to enable the entire machine to be operated in an efficient manner, and to be constructed and assembled 25 economically and with facility, and in such a manner as to afford the required strength, and reduce the friction to a minimum when the machine is in operation. It will also be noted that the paddle wheels 123, and 124' 30 are adapted to be used in place of the intermediate feed rolls 111, 114, if desired.

I claim:

1. In a fiber treating machine of the class described, the combination of a pair of pivoted shaker jaws spaced apart and adapted to admit fibrous material therebetween to be operated upon thereby, means for delivering fibrous material in position to pass between the pivoted jaws, and means for operating the jaws.

2. In a fiber treating machine of the class described, the combination of a pair of pivoted shaker jaws spaced apart and adapted to admit fibrous material between the jaws to be operated upon thereby, fiber-supporting means located forward of the pivoted jaws and adapted to deliver fibrous material in position to pass between the same, means for operatively connecting the jaws, and means for operating the jaws.

3. In a fiber treating machine of the class described, the combination of a pair of reciprocating shaker jaws spaced apart and adapted to admit fibrous material between the jaws, to be operated upon thereby, fiber-supporting and feeding mechanism located forward of the reciprocating jaws and adapted to deliver fibrous material in position to pass between the same, and means for reciprocating the shaker jaws.

4. In a fiber treating machine of the class described, the combination of a pair of reciprocating shaker jaws spaced apart and adapted to admit fibrous material therebetween to be operated upon thereby, supporting pivot mechanism in supporting engagement with the forward portions of the jaws adapted to permit the rear portions of the jaws to swing upward and downward back of the supporting pivot mechanism, fiber-engaging mechanism located forward of the shaker jaws and adapted to deliver fibrous material in position to pass between the jaws during the operation of the jaws, and means for operating the jaws.

5. In a fiber treating machine of the class described, the combination of a pair of shaker jaws spaced apart and adapted to admit fibrous material therebetween to be operated upon thereby, fiber supporting and feeding mechanism located forward of the shaker jaws and adapted to deliver fibrous material progressively in position to pass between the jaws, to be operated upon thereby, supporting pivot mechanism in supporting engagement with the beater jaws and adapted to permit the rear portions of the jaws to swing upward and downward back of the axes of the jaws during the passage of fibrous material between the jaws, and shaker-jaw operating mechanism operatively connected with the shaker jaws and with the feeding mechanism.

6. In a fiber treating machine of the class described, the combination of a pair of pivoted shaker jaws spaced apart and adapted to admit fibrous material therebetween to be operated upon thereby, feeding mechanism located forward of the shaker jaws and adapted to feed a layer of fibrous material progressively between the jaws during the operation of the latter, a crank shaft operatively connected with the shaker jaws, and means for operating the crank shaft.

7. In a fiber treating machine of the class described, the combination of a pair of pivoted shaker jaws spaced apart and adapted to admit fibrous material between the jaws to be operated upon thereby, the rear portions of the jaws being free to swing upward and downward back of the axes of the jaws, a jaw-operating shaft rotatively mounted in a suitable support, and eccentric mechanism on the shaft and operatively connected with the shaker jaws, for operating the same during the passage of fibrous material between the jaws.

8. In a fiber treating machine of the class described, the combination of a pair of pivoted shaker jaws spaced apart and adapted to admit fibrous material therebetween to be operated upon thereby, the rear portions of said jaws being free to swing upward and downward back of the axes of the jaws, shaft and gear mechanism operatively con-

nected with the shaker jaw mechanism, for reciprocating the same during the passage of fibrous material between the jaws, and fiber-engaging means located back of the shaker jaws and adapted to engage fibrous material passing rearward between the jaws as such material is shaken upward and downward by the pivoted jaws.

9. In a fiber treating machine of the class described, the combination of a pair of oscillating shaker jaws spaced apart and adapted to admit a layer of fibrous material progressively between the jaws during the operation of the latter, supporting hinge mechanism in supporting engagement with the jaws and adapted to permit the rear portions of the jaws to swing upward and downward back of the axes of the jaws, fiber-engaging and supporting mechanism located forward of the shaker jaws and acting to deliver fibrous material progressively in position to pass between the jaws during the operation of the same, means for operating the jaws, and rotative fiber-engaging means located rearward with respect to the shaker jaws and acting to engage and feed rearward fibrous material as such material is delivered and operated upon by the upwardly and downwardly swinging rear portions of the jaws.

10. In a fiber treating machine of the class described, the combination of a pivoted shaker jaw comprising in its construction an oscillating plate the rear portion of which is adapted to oscillate back of the axis of such jaw, a second pivoted shaker jaw mounted in approximately parallel relation to the first-mentioned jaw, and spaced apart with respect to said first-mentioned jaw to permit fibrous material to pass between the jaws, fiber-supporting means located forward of the shaker jaws and adapted to deliver fibrous material in position to pass rearward between the jaws, and means for operating the jaws.

11. In a fiber treating machine of the class described, the combination of a pivoted shaker jaw comprising an oscillating plate provided with a series of ribs, the rear por-

tion of said jaw being adapted to swing upward and downward back of the axis of the jaw a second jaw pivotally mounted in approximately parallel relation to and operatively connected with the first-mentioned jaw and spaced apart with respect to the same to provide a passage having an upper wall formed by the first-mentioned jaw and a lower wall formed by the last mentioned jaw adapted to permit fibrous material to pass rearwardly between the jaws while the latter are in operation, and means for reciprocating the jaws.

12. In a fiber treating machine of the class described, the combination of a pivoted shaker jaw the main body of which consists of a ribbed plate the rear portion of which is adapted to swing upward and downward back to the axis of the jaw, a second jaw pivotally mounted adjacent to and spaced apart with respect to the first mentioned shaker jaw and adapted to admit fibrous material between said jaws during the operation of the same, means for operatively connecting said jaws, means for delivering fibrous material in position to pass rearward between the jaws, and shaft and gear mechanism operatively connected with the shaker jaw mechanism, for operating the same.

13. In a fiber-treating machine, the combination of a fiber-supporting shaker member pivotally mounted and having its rear margin located rearward with respect to and adapted to swing upward and downward back of the axis of said shaker member, and means for feeding fibrous material rearward transversely with respect to said axis and across the rear upwardly and downwardly swinging margin of said shaker member, and means for reciprocating said pivoted shaker member.

Signed at Chicago, Illinois, this 29th day of May, 1920.
